UNITED STATES PATENT OFFICE.

JOSEPH LYLE, OF CLARKSVILLE, IOWA.

SEEDING-MACHINE.

Specification forming part of Letters Patent No. 44,328, dated September 20, 1864.

To all whom it may concern:

Be it known that I, JOSEPH LYLE, of Clarksville, in the county of Butler and State of Iowa, have invented a new and Improved Broadcast-Seeding Machine; and I do hereby declare that the following is a full, clear, and exact description of the same, reference being had to the accompanying drawings, making a part of this specification, in which—

Figure 1 is a side sectional view of my invention, taken in the line x x , Fig. 2; Fig. 2, a plan or top view of the same, the back of the seed-box being in section or partly broken away.

Similar letters of reference indicate corresponding parts in the two figures.

This invention consists in the employment or use of a series of agitators attached to a horizontal rod, which is connected to levers operated from a crank-shaft which receives its motion from one of the traction-wheels of the machine. The agitators are rods which work at the rear of the seed-box and in the same through openings made in the back of the seed-box, the area or capacity of the openings being regulated by means of a slide, as hereinafter set forth.

To enable those skilled in the art to fully understand and construct my invention, I will proceed to describe it.

A represents a seed-box, the bottom a of which is slightly inclined, so that its rear end will be a trifle lower than its front end, as shown in Fig. 1. This seed-box has a draft-pole, B, attached to it, and it is mounted on two wheels, C C', the axle D of which rotates in bearings secured to the under side of the seed-box.

To the inner side of the wheel C there is attached a toothed wheel, E, which gears into a pinion, F, at one end of a shaft, G, the bearings of which are at the front part of the seed-box A. This shaft G is allowed to slide longitudinally in its bearings, and it may be thus moved when desired to throw the pinion F in and out of gear with wheel E by means of a lever, H, the lever end of which is fitted between collars b b on shaft G. The lever H passes up through a slot, c, in a plate, I, attached to the front part of the seed-box, said slot having two notches, d d, one to hold the lever H, so that the pinion F may be retained

in gear with the wheel E, and the other to hold it out of gear.

On the end of the shaft G opposite to that where the pinion F is attached there is a crank, J, to which the front end of a pitman, K, is connected, the back end of said pitman being attached to a right-angular or bell crank, L, at the back part of the seed-box, at one side of it, and to this bell-crank one end of a bar, M, is connected by a pivot, the opposite end of said bar being connected by a pivot to a lever, N, at the opposite side of the seed-box. The bar M has a series of rods, O, attached to it, and these rods pass through openings d in the back of the seed-box. The rods O are curved slightly upward at their ends, as shown in Fig. 1.

P is a slide, the ends of which are fitted in vertical grooves e e at the back part of the seed-box, one at each side, as shown in Fig. 2. This slide is directly between and in contact with the back of the seed-box, and by adjusting said slide higher or lower, the capacity of the openings d may be varied as desired. The slide P may be thus adjusted by means of nuts e', fitted on vertical screws f, attached to the slide and passing through guides g, attached to the upper edge of the back of the seed-box.

Q is the driver's seat at the end of a curved support, R, secured to the front part of the seed-box.

As the machine is drawn along the shaft G is rotated from the wheel C by means of the gearing E F, and the crank J and pitman K communicate a vibratory movement to lever L, which gives a reciprocating movement to the bar M and the rods or agitators O, which cause the seed to be discharged through the openings d in a broadcast manner.

In order to render the machine inoperative, the shaft G is moved through the medium of lever H, so as to throw the pinion F out of gear with the wheel E.

The seed-box A is balanced, or nearly so, on the axle D, so that the team is relieved from the weight of the device, and the agitators or rods O are operated with but little friction. The wheel C is made to operate the shaft G, as it is secured to the axle, the latter rotating in its boxes or bearings. The wheel C' is placed loosely on the axle. The seed is discharged in a uniform and perfect manner.

Having thus described my invention, what I claim as new, and desire to secure by Letters Patent, is—

The combination of the inclined floor *a*, apertures *d d*, gate *P*, and agitating device *J K L M N O*, having curved teeth projecting from the outside into the hopper horizontally through the apertures *d d*, and all constructed,

arranged, and operating in the manner and for the purposes herein specified.

JOSEPH LYLE.
